OTHER PUBLICATIONS

Design U.S. Appl. No. 29/624,451, filed Nov. 1, 2017 in the name of Newtl.

Primary Examiner — Darlington Ly(74) *Attorney, Agent, or Firm* — Carter, Deluca & Farrell LLP(57) **CLAIM**

The ornamental design for a vehicle partition, as shown and described.

DESCRIPTION

FIG. 1 is a front perspective detailed view of a vehicle partition without glass between the driver and the passenger entry in the bus in accordance with the present design;

FIG. 2 is a front elevational view thereof;

FIG. 3 is a rear perspective view thereof;

FIG. 4 is a left side elevational view thereof;

FIG. 5 is a right side elevational view thereof; and,

FIG. 6 is a top plan view thereof.

1 Claim, 6 Drawing Sheets(56)
